UNITED STATES PATENT OFFICE.

GUSTAV PÖHL, OF GOSSNITZ, GERMANY.

TRACTION-WHEEL.

1,192,345.

Specification of Letters Patent. Patented July 25, 1916.

Application filed February 12, 1915. Serial No. 7,767.

To all whom it may concern:

Be it known that I, GUSTAV PÖHL, subject of the Emperor of Germany, and a resident of Gossnitz, Germany, have invented 5 certain new and useful Improvements in Traction-Wheels, of which the following is a specification.

The main driving wheels of the motor-plows are constructed as gripper-wheels, 10 whereby the gripper points or gripper shovels are pushed forward and drawn back by radially directed arms. It is a known construction to link these arms to an adjusting ring, which is mounted concentri- 15 cally to the axle of the wheel. In order to turn this adjusting ring a special lever-system is employed, producing a great number of fulcrums which are exposed to considerable strain and wear, especially because 20 it is impossible to protect them against dust. But the action of the driving wheels depends entirely on the correct adjustment of the arms.

According to the present invention the 25 ring, to which the gripper-arms are linked, is provided with internal teeth, by which it engages an annular groove of the hub and may be adjusted by a pinion mounted in the hub.

30 The present invention is shown in the accompanying drawing, in which—

Figure 1 shows part of a gripper-wheel in elevation, some parts of the wheel being shown in section; Fig. 2 is a top view partly 35 in section.

In the form shown on the drawing the wheel proper A, supported by the spokes B, consists of two angular wheel rims A¹ A², kept at the required distance from each 40 other by cross braces C. The grippers D are radially mounted between the two wheel rims. The grippers are made of sheets of steel or another suitable material, which have the form of spades and are strength- 45ened by longitudinal ribs D¹ D² which may be pressed out of the steel sheet in the form of hollow ribs.

The shovel-shaped ends of the grippers D must be guided through the rim. To 50 effect this, pivotally mounted guides E with slits, through which the gripper-plates D project, are employed in the present case. In the form illustrated the guides have the form of cylindrical bolts, whose pins are 55 guided in the rims A¹ A² of the wheel. These guides may be constructed of a single piece

or they may be employed as elements which are longitudinally split into two parts. They must be mounted in the rims in such a manner, that they may carry out an unhampered 60 rotation, in order to be able to follow the different positions of the gripper-plates D.

For adjusting the grippers D their arms F are linked by bolts I pivotally mounted on a ring G, concentric with the axle H of 65 the wheel. By a slight turning of the ring the arms may be brought into the position indicated by dotted lines and the grippers D may be drawn back. The guide-bolts E allow of this slanting position, because they 70 are themselves pivotally mounted in the casting of the wheel.

According to the present invention the ring G is provided with internal teeth which engage the annular groove of the hub K. 75 A pinion L, pivotally mounted inside the hub, engages the internal gearing of the ring. By a turning of the gear the ring G is consequently adjusted.

As only a partial turning of the ring G 80 is required, it is necessary to provide the latter only on a portion of its periphery with teeth, while the other portion of the ring may remain plain.

The required position of the grippers may 85 be obtained by adjusting pins. If the ring G is provided, on the one hand, with holes M at determined distances from each other with corresponding holes in the adjacent walls as shown in Fig. 1, the corresponding position 90 of the grippers D may be secured by an adjusting pin, passing through said holes. The same effect may, however, also be attained by providing the ring on its entire internal periphery with teeth and employing 95 a wedge N, as shown in Fig. 2, for limiting the position of the grippers, which wedge must be provided with teeth. These teeth engage those of the internal gearing of the ring G, thus obviating its further turning 100 and, consequently, any disarrangement of the arms. This disposition allows of a very precise shifting of the gripper for one tooth at each time.

In the present form the traverses C of the 105 wheel-frame are formed of flat bar irons placed edgewise, in order to make the edges penetrate the soil more easily and to facilitate also the operation of the grippers if the same are withdrawn. By this arrangement 110 a breaking of the ground takes place between the aforesaid traverses while the plow

is driving. The superfluous openings along the periphery of the wheel may be covered by plates A³. But always a sufficiently large space must remain in the neighborhood of the shovels D, out of which the earth cut out and settled therein may again fall down during the drive, so that the grippers automatically clean themselves from the earth adhering to them.

10 What I claim as my invention and desire to secure by United States Letters Patent is—

1. A gripper wheel for motor plows comprising adjustable gripper arms with gripper plates thereon, a wheel proper composed of two wheel rims, and guides with slits pivotally mounted in the walls of the wheel rims, said gripper plates passing through the slits and adapted to project beyond the 20 wheel rims.

2. A gripper wheel for motor plows comprising adjustable gripper arms with grippers thereon, two angular wheel rims beyond which said grippers reach, traverses spacing 25 the angular portions of the rim apart, guides pivotally mounted in the walls of the wheel having slits through which the grippers pass, and inner mechanism for moving the gripper arms with the grippers mounted 30 within the hub of the wheel so as to protect it against clogging by soil.

3. A gripper wheel for motor plows comprising adjustable gripper arms with grippers thereon, two angular wheel rims beyond

which said grippers reach, traverses for 35 spacing said angular portions, inner mechanism for moving the gripper arms consisting essentially of a ring to which the grippers are linked having teeth on the inner surface, and a pinion, said gear mechanism being 40 covered by the said ring.

4. In a gripper wheel for motor plows having gripper arms with grippers thereon and angular wheel rims with traverses spacing them apart, an adjusting device for 45 drawing the grippers in and out and consisting essentially of a ring with interior gear and pinion mechanism, and means for locking the ring in the adjusted position, so arranged that the adjusting device is protected against clogging by soil.

5. In a gripper wheel for motor plows having gripper arms with grippers thereon and angular wheel rims with traverses spacing them apart, a guiding device for the 55 grippers composed of cylindrical bolts mounted in the wheel rims and having slits through which the grippers pass, means for drawing said grippers in and out, and means for securing the grippers in the desired 60 position.

Signed at Leipzig, Germany, this 14th day of January, 1915.

GUSTAV PÖHL.
